UNITED STATES PATENT OFFICE.

BENEDETTO GILIBERTI, OF NEW YORK, N. Y.

VIBRATOR.

1,416,281.

Specification of Letters Patent. Patented May 16, 1923.

Application filed May 12, 1921. Serial No. 468,938.

To all whom it may concern:

Be it known that I, BENEDETTO GILIBERTI, a citizen of the United States, and resident of the city of New York, in the county of 5 Kings and State of New York, have invented certain new and useful Improvements in Vibrators, of which the following is a specification.

The present invention relates to improvements in therapeutic vibrators, commonly known as massage vibrators. The invention pertains more particularly to that type of vibrators, wherein a vibrator head is mounted upon a holding device, having 15 straps into which the hand of the operator is extended.

The main object of the invention is to provide a connection between the vibrator head and the holding device thereof, that permits 20 the connected parts to be turned in any direction in relation to one another.

Another object of the invention is to provide a connection of the character mentioned, which is simple in construction, efficient in 25 operation and one which is capable of manufacture on a commercial scale, or in other words one which is not so difficult to produce as to be beyond the reasonable cost of such a contrivance.

With these and other objects in view, which will more fully appear as the nature 30 of the invention is better understood, the same consists in the combination, arrangement and construction of parts hereinafter described, pointed out in the appended claim and illustrated in the accompanying drawings, it being understood that many changes may be made in the size and proportion of the several parts and details of 35 construction within the scope of the appended claim, without departing from the spirit or sacrificing any of the advantages 40 of the invention.

One of the many possible embodiments of 45 the invention is illustrated in the accompanying drawings, in which:—

Figure 1 is a side elevation of a vibrator constructed in accordance with the present invention; Fig. 2 is a plan view thereof, with 50 the elements in other positions; and Fig. 3 is a section taken on line 3—3 of Fig. 1, on a larger scale.

In the drawings, the numeral 10 indicates a vibrator head, in the form of a cylindrical hollow body, in which is disposed a rotor of 55 any suitable type. This rotor is not shown, as it does not form part of the present in-

vention. The rotor is driven from a suitable source of power by the intermediary of a flexible shaft, that extends into the head 10 through a bearing member 11 thereon. The vibrator head is mounted upon a holding device, including a curved plate member 12, to the ends of which are fixed in any suitable manner loop-straps 13, through which the hand of the operator may be extended. The connection between the plate member 12 and the vibrator head is made by a universal joint of any suitable construction. In the case illustrated in the drawings, the universal joint includes a spindle 14, that is rotatably arranged in the bore 15 of a boss 16, the latter being, preferably, made integral with the vibrator head 10. In order to hold the spindle in position within the bore 15, the said spindle may be provided with a peripheral circular groove 17, into which extend screws 18 on the boss 16. The spindle is attached to or made integral with a fork-shaped lug 19, straddling an ear 20, the latter being centrally arranged upon the plate member 12. Through the lug and ear extends a pin 21 in a direction at right angles to the longitudinal axis of the spindle 14.

In use, the operator extends the fingers of 85 one hand, with the exception of the thumb, through the straps 13, resilient blocks 22 on the plate member 12 resting on the back of the hand, the fingers being free to work on the body to be massaged. The universal 90 joint permits the holding means, that is to say the plate member 12, to be moved in relation to the vibrator head 10 in a plane at right angles to the longitudinal axis of the spindle 14 and furthermore in a plane at 95 right angles to said first mentioned plane. The operator is thus in a position to move the hand in all directions without changing materially the position of the vibrator head. Undue strains on the latter and on the flexible 100 shaft are thus effectively prevented.

What I claim is:—

A vibrator including a head having a boss provided with a bore, a spindle rotatably mounted in said bore having a lug, a holder 105 for said head having an ear, and a pin extending through said lug and ear in a direction at right angles to the longitudinal axis of said spindle.

Signed at New York, in the county of New 110 York and State of New York, this 28th day of April, A. D. 1921.

BENEDETTO GILIBERTI.
